UNITED STATES PATENT OFFICE.

ARTHUR M. SMITH, OF CLEVELAND, OHIO.

REGULATING DEVICE.

Application filed July 16, 1917. Serial No. 180,700.

To all whom it may concern:

Be it known that I, ARTHUR M. SMITH, a citizen of the United States, residing at Cleveland, in the county of Cuyahoga and State of Ohio, have invented a certain new and useful Improvement in Regulating Devices, of which the following is a full, clear, and exact description.

This invention relates to a controlling apparatus for use with a heating furnace or similar apparatus in connection with which fluid fuel and air are supplied to the furnace, and in which the passage of fuel gases to a stack or flue are controlled.

15 The object of the invention is to provide an apparatus of the character described in which by a unitary apparatus the supply of fuel and air as well as the passage of flue gases to the stack are controlled so that an 20 interdependent relationship when once established, may be maintained.

Generally speaking, the invention may be said to comprise the elements and combinations thereof set forth in the accompanying 25 claims.

Reference should be had to the accompanying drawings forming a part of this specification in which in Fig. 1 there is somewhat diagrammatically shown the relationship between the parts to be controlled and the apparatus for controlling them, Fig. 2 is a front elevation with portions in section of a furnace with which is associated the regulator of my invention; Fig. 3 is a 35 side elevation with portions in section of the construction shown in Fig. 1.

The apparatus is more particularly intended for use in connection with furnaces in which coal is coked, or materials are 40 heated or calcined, although it will be apparent that the apparatus is susceptible of other and more varied use.

In a coking furnace or calcining furnace, the furnace itself as is well known, comprises a retort or oven A which is usually heated through the instrumentality of gas burned with a proper quantity of air, the burning taking place adjacent the walls of the oven so that the oven is heated.

50 The products of combustion are usually conducted from the furnace through checker brick-work or passageways such as B, and thence to a stack or flue.

The gas, which in burning is utilized to 55 heat the oven, may be supplied from a producer C or from any other source of gas,

and the apparatus herein described contemplates, in the event that the gas supplied is from a producer, the use of a connection which will control the supply of air, and 60 possibly the supply of steam also, to the producer so that the quantity of gas produced in the producer may be controlled.

All such heating furnaces as that to which reference has been made, require some control with respect to the passage of the 65 burned gases or products of combustion to the flue, for the stack draft has an important bearing upon the heating of the retort chamber of such a furnace.

70 For purposes of more ready understanding of the invention it is explained that the pipe 1 is connected in some suitable manner with the combustion chamber or flue of a furnace such as a flue B and a portion of 75 the burned gases or products of combustion will pass through the pipe 1.

Associated with the pipe 1 is a hollow receptacle 2 having a chamber 3, the products of combustion passing into the chamber 80 3, and from the chamber 3 to a pipe 4 which is connected to a larger pipe 5, which is a flue for conducting products of combustion from the furnace and which is connected with the stack 6. It will be noted 85 that the pipe 4 in effect communicates directly with the stack 6, for its connection with the pipe 5 is beyond the damper 5^a shown therein, so that the suction effect upon the pipe 4 is the same as that in the 90 stack 6.

The pipe 5 is directly connected with that portion of the furnace through which the products of combustion pass, and receives the products of combustion from the chamber in which they have been burned, or 95 from the regenerative checker brick-work through which they may have passed, and the passage of the products of combustion from the furnace through the pipe 5 is controlled by the damper 5^a.

At 7 there is represented a conduit having an opening which is controlled by a damper 8, and at 9 a second conduit is shown, having an opening which is controlled by a 105 damper 10. The portions 10^b and 11 which are associated with the pipe 9, are simply control passageways connecting with the furnace.

The pipe 9 may be described as a conduit 110 through which air is supplied to the furnace by means of a conduit 9^a to support com-

bustion of the gas to be burned adjacent the heating chamber or retort, and the passage of air to the pipe 9 is controlled by the damper 10.

5 The conduit 7 may be described as suitably connected with a gas producer for the purpose of supplying air to the producer, which, as is well understood, produces such a partial combustion of the coal therein as 10 to produce a gas which may be used as a fuel gas.

The damper 10 is by a suitable articulated connection 10^a, secured to a rod or similar device 12. Similarly the damper 8 15 is by a connection 8^a connected with the part 12, and the damper 5^a is also connected with the part 12 so that as the part 12 may be moved in one direction or the other, the dampers 10 and 8 will be moved to close or 20 open the passages which they control, and the same is true with respect to the damper 5^a.

The rod 12 extends within the casing 13 and is operated to move in one direction by 25 means of a spring 14 which surrounds the end of the rod 12 which is within the casing 13. The end of the rod engages with a flexible diaphragm 15 which extends transversely with respect to the casing 13, and 30 with the top part of the casing 13 forms a chamber.

This chamber communicates with a thermostatic device comprising a tube 16, which tube in turn communicates with a vessel 17 35 containing a fluid such as air or any other suitable fluid which upon heating, expands. This receptacle 17 is surrounded in part by the casing 2 so that the fluid content of the receptacle 17 is heated by the hot gases 40 which pass through the pipe 1.

Expansion of the fluid within the receptacle 17, which fluid, of course, fills the pipe 16 and the chamber formed above the diaphragm in the receptacle 13, causes a pressure to be exerted against the rod 12, which 45 moves the rod and consequently moves the various dampers which are associated with the rod. When such pressure is relieved, the rod under the action of the spring 14 moves 50 in an opposite direction.

It will be understood that expansion of the fluid content of the receptacle 17 is induced by an increase in temperature of the gases passing through the pipe 1, and of 55 course the temperature of the gases passing through the pipe 1 is indicative of the heat supplied to the heating chamber or retort. Consequently a rise in the temperature of the flue gases above a predetermined point, 60 clearly indicates the necessity for diminishing the supply of fuel gas and of air which is burned to heat the retort.

It will be obvious that increase in the temperature of the gases passing through the 65 chamber 3 will expand the fluid within the

receptacle 17, which will in turn cause the rod 12 to be depressed and thereby move the dampers 10, 8 and 5 to close to a certain degree, the openings which they control. This would mean that the amount of fuel gas supplied to the furnace would be diminished as well as the quantity of air supplied for the combustion of that gas, and also the draft suction between the stack and the furnace will be decreased by the operation of 70 the damper 5^a. The various operations which have just been described, when effected will result in causing a lowering of the temperature of the heating furnace or retort. Obviously the reverse operation of 75 the rod 12 will result in the opposite condition taking place.

In the previous part of the specification I have referred to the conduit 7 as an air and possibly steam conduit through which these 80 elements are supplied to a producer. It will be obvious that this conduit 7 may receive gas from any source which is supplied to the furnace to be heated, and under such circumstances the gas thus supplied will be controlled by the damper 8, and whether the conduit 7 be for the purpose of supplying air to a producer or of supplying gas directly to the heating furnace, the functional relationship with respect to the air supply 90 through the conduit 9 as well as the controlled relationship with respect to the damper 5^a is the same. The pipe 4 has inserted therein a damper 20, this damper being moved in or out by a handle 21 so as to control the passage of the products of combustion which pass through the pipe 4. In connection with the pipe 4 there is a draft gauge or indicator 22 which may be of any preferred type and as its name indicates, 100 will show the suction produced by the gases passing through the pipe 4.

It will be obvious that by manipulation of the damper 20 the suction in the pipe 4 may be controlled so as to keep that suction 110 uniform if this be desired.

This control of the gases passing through the pipe 4, has its effect upon the thermostatic device as will readily be understood, so that the regulation of the furnace may be 115 accomplished with the apparatus herein described and the effect of the stack draft controlled as well.

Having described my invention, what I 120 claim is:

1. The combination with a furnace having an air conduit with means for controlling the same and having a fuel conduit and means for controlling the same, said furnace having a flue, a damper in said flue, means 125 connecting the damper with the aforesaid means for controlling the air conduit and the fuel conduit whereby they operate in predetermined relationship, a thermostatic device connected with the aforesaid connect- 130

ing means, a conduit conducting heated gases from the furnace to the said flue, said thermostatic device being associated with the last mentioned conduit and sensitive to the heat of gases passing therethrough.

2. The combination of a furnace having a flue gas conduit, a flue with which the said conduit connects, a damper in said flue gas conduit, a thermostatic device associated with said conduit, said furnace being provided with an air conduit and with a fuel conduit, controlling means for said conduits, a common connection between the said controlling means and the aforesaid damper in the gas conduit, said connecting means being operatively connected with the thermostatic device to be moved thereby.

3. The combination of a furnace having

a conduit for conducting flue gases, a flue with which the conduit connects, a damper 20 associated with the said conduit whereby suction in said conduit may be maintained constant, a thermostatic device having the heat sensitive part thereof associated with the said conduit and the gases passing therethrough, said furnace having an air conduit and a fuel conduit, means associated with each conduit for controlling the same, a common connecting means for the damper and the aforesaid controlling means, said 30 common connection being operatively connected with the thermostat to be moved thereby.

In testimony whereof, I hereunto affix my signature.

ARTHUR M. SMITH.
